UNITED STATES PATENT OFFICE.

FRANK RUDOLPHI, OF NEW YORK, N. Y., ASSIGNOR TO AMERICAN CAN COMPANY, OF NEW YORK, N. Y., A CORPORATION OF NEW JERSEY.

CAN-BODY-FLANGING MACHINE.

1,318,412.

Specification of Letters Patent.

Patented Oct. 14, 1919.

Application filed May 11, 1911. Serial No. 626,634.

To all whom it may concern:

Be it known that I, FRANK RUDOLPHI, a citizen of the United States, residing in New York, in the county of New York and State 5 of New York, have invented a new and useful Improvement in Can-Body-Flanging Machines, of which the following is a specification.

My invention relates to improvements in 10 can body flanging machines.

The object of my invention is to provide a can body flanging machine of a simple and efficient construction, composed of relatively few parts and capable of being 15 cheaply manufactured, which will operate rapidly and serve to form accurate, true and uniform flanges upon the opposite ends of can bodies.

My invention comprises, in coöperative 20 combination a can body chute, an intermittently moving can body carrier furnished with a series of can body receiving and holding pockets, and preferably consisting of 25 a pair of rotating turrets furnished with segmental can body pockets adapted to register together at each step and to convey the can bodies one by one from the can body chute into position between the flanging dies, and 30 a pair of reciprocating flanging dies 35 forming in size and shape to the can body and adapted to enter within the same and turn or form flanges on the opposite ends of the can body simultaneously around the whole circumference thereof, each of the 40 flanging dies having a limiting wall or ring to cause the flanges to form truly and uniformly and equally on each end of the can body, the can body carrier coöoperating to strip the flanged can body from the flanging dies as they withdraw and to convey 45 and discharge the flanged can body into the discharge chute. My invention also consists in the novel construction of parts and devices and in the novel combinations of 50 parts and devices herein shown and described and more particularly specified in the claims.

In the accompanying drawing forming a part of this specification, Figure 1 is a front 55 elevation of a can body flanging machine

embodimenting my invention. Fig. 2 is an end elevation. Fig. 3 is an end elevation, partly in vertical section, on the broken line 3—3 of Fig. 1. Fig. 4 is a vertical section on line 4—4 of Fig. 1. Fig. 5 is a detail plan of 55 certain parts, partly in horizontal section, on lines 5—5 of Fig. 1. Fig. 6 is a detail, horizontal section of the flanging dies on line 6—6 of Fig. 4. Fig. 7 is a detail section on line 7—7 of Fig. 1, and Fig. 8 is an enlarged, 60 detail sectional view of one of the flanging dies.

In the drawing, 1 represents the frame of the machine, 2 the can body chute, preferably arranged upright and composed of 65 two pairs of angle bars carried by adjustable brackets 3 on the frame 1. 4 is an intermittently rotating can body carrier furnished with a series of segmental receiving pockets or holders 5. The can body pockets 70 or holders 5 are preferably formed for convenience of construction in two separate piece carrier disks 4, 4 secured to a common carrier shaft 6. I prefer to employ two can body carriers 4, each with a series of 75 can body pockets or holders 5 and arrange them to intermittently rotate together so that the segmental pockets on one carrier register with those on the other, the carrier shafts 6, 6 being geared together by intermeshing gears 7 thereon. By employing two sets of intermittently rotating segmental can body pockets or holders and carrier disks, the can bodies may be very rapidly fed or conveyed one by one from the 80 can body chute by a positive movement into position for operation of the flanging dies thereon and subsequently discharged from the machine into the discharge chute 8 which is arranged below the flanging dies and can 85 body carriers 4. The can body carriers 4 turn about horizontal axes and have their segmental can body pockets or holders 5 horizontally disposed so that the can bodies may feed by 90 gravity down the chute into position to be grasped by the radially projecting arms 9 of the carriers 4 between adjacent pockets 5.

The machine is provided with two horizontally and simultaneously reciprocating 100

can body flanging dies 10, each having a tapering head or nose 11 to facilitate the entrance of the die within the end of the can body when the can body is bent or 5 distorted out of shape, and each also provided with a limiting ring, wall or shoulder 12, preferably formed in a separate piece from the die for convenience of construction, and against which the extreme 10 outer edge 13 of the flange 14 of the can body 15 may engage and thus limit the extent to which the flange will be turned upon each end of the can body as the flanging dies 10, 10 enter the can body at the opposite 15 ends thereof and approach each other. Each of the dies 10 is carried by a plate or holder 16, having a hub 17 fitting within the die 10 and carried by the reciprocating stem 18 which is mounted to slide in a suitable bearing or guide 19 on the frame 1 of the machine. The flange limiting wall ring 12 when made, as shown in the drawing, in a separate piece from the die 10, is preferably furnished with an inwardly projecting 25 flange 20 to cause it to be held in position on the plate or holder 16 by the die 10.

The dies are reciprocated as required, preferably by means of cams 21 on the cam shaft 22 through fork levers 23 pivoted at 30 24 to the frame of the machine and carrying rollers 25 at their lower ends for engagement with the cams, and which engage at their upper ends collars 26 adjustably secured on the reciprocating stems 18 35 of the dies.

The can body carriers 4 are preferably intermittently rotated as required from the continuously rotating cam shaft 22 by a radially slotted or Geneva stop wheel 28 on 40 one of the carrier shafts 4 which is engaged by pins or anti-friction rollers 29 on the disk 30 secured to the cam shaft 22.

The cam shaft 22 is continuously rotated from the driving shaft 31 through the intermeshing gears 32, 33. The driving shaft is furnished with a driving pulley 34 and the customary clutch 35 and clutch lever 36 for stopping and starting the machine.

The two sets of carrier disks 4, 4 and 4, 4 50 are spaced apart on their respective carrier shafts 6, 6, preferably about as illustrated in Fig. 6 so that when the dies 10, 10 separate or withdraw from each other after the flanging operation is completed, the carrier 55 disks will themselves serve, by engagement with the flanges formed on the can body, to strip or disengage the can body from the dies in case the flanged can body should tend to stick in either die. Each pair of 60 carrier disks 4, 4 on each of the shafts 6 may be adjustably secured to the shafts so that they may be adjusted closer together or farther apart for operation upon can bodies of different lengths. The two pair

of angle irons forming the chute may be 65 also adjusted closer together or farther apart for the same purpose of adapting the machine for operation upon can bodies of different lengths. By adjusting the collars 26 on the operating stems 18 of the dies 70 closer together or farther apart, the dies are adapted for operation upon can bodies of different lengths.

I claim:—

1. In a can body flanging machine, the 75 combination with a can body carrier comprising intermittently rotating can body holders, of a pair of reciprocating flanging dies mounted on the frame of the machine and each conforming in size and shape to 80 and adapted to enter within the mouth of the can body, said carrier coöperating with said dies as they withdraw to strip or discharge the flanged can body from the dies by engaging behind the flanges which have been produced on the can body, substantially as specified.

2. In a can body flanging machine, the 90 combination with a can body carrier comprising intermittently rotating can body holders, of a pair of reciprocating flanging dies mounted on the frame of the machine and each conforming in size and shape to 95 and adapted to enter within the mouth of the can body, each of said flanging dies having a flanging limiting shoulder, said carrier coöperating with said dies as they withdraw to strip or discharge the flanged can body from the dies by engaging behind the flanges which have been produced on the 100 can body, substantially as specified.

3. In a can body flanging machine, the 105 combination with two intermittently moving can body carriers rotating together and furnished with a plurality of segmental can body holders, of a pair of reciprocating flanging dies movable crosswise of the said carriers on the frame of the machine, said carriers coöperating with said flanging dies 110 to strip the flanged can bodies from the dies as the dies are withdrawn and then to carry the can body away from the line of the dies, substantially as specified.

4. In a can body flanging machine, the 115 combination with two intermittently rotating carriers turning together about a horizontal axis and each furnished with a plurality of segmental can body holders, of a reciprocating flanging die movable transversely to said holders, and conforming in 120 size and shape to and adapted to enter within the end of the can body and turn a flange thereon and provided with a limiting wall, said carriers coöperating with said die to free the flanged can body from the die as 125 it withdraws, substantially as specified.

5. A can body flanging machine including, in combination: a reciprocating, sub-

stantially solid, flanging die conforming in size and shape to a can body and adapted to enter the same; means for conveying can bodies to a position in alinement with said die; mechanism for reciprocating said die; and adjustable means for varying the path of reciprocation of said die to thereby adapt it for operation on can bodies of different lengths.

FRANK RUDOLPHI.
